CLAIM

An ornamental design for a fascia tissue fitness device with integrated brush elements, as shown and described.

DESCRIPTION

FIG. 1 is an illustration of a top perspective view of a fascia tissue fitness device with integrated brush elements, according to an illustrative embodiment;

FIG. 2 is an illustration of a front elevation view thereof;

FIG. 3 is an illustration of a rear elevation view thereof;

FIG. 4 is an illustration of a right-side view of thereof;

FIG. 5 is an illustration of a left-side view thereof;

FIG. 6 is an illustration of a top view thereof;

FIG. 7 is an illustration of a bottom view thereof;

FIG. 8 is an illustration of a bottom perspective view thereof; and,

FIG. 9 is an illustration of a top perspective, exploded view thereof.

The broken lines shown in the drawings are for the purpose of illustrating portions of the fitness tissue device with integrated brush elements, which form no part of the claimed design.
